AUTOMATIC SIGNAL LOCK AND RELEASE
FOR SWITCHBOARDSHenry Koch, Jamaica, N. Y., assignor to Dictograph Products Company Inc., New York, N. Y.,
a corporation of Delaware

Application August 11, 1932, Serial No. 628,291

6 Claims. (Cl. 179—92)

This invention relates to signal devices and the operating mechanism therefor of telephone switchboards and the like and, more particularly, to such devices of the visual type which will 5 operate and remain in a signaling position when the switchboard is not in use.

A general object of the invention is the provision of such a device which efficiently operates to indicate an incoming call, such indication being 10 maintained until an attempt is made to answer the call, the structure being simple and rugged and automatically operable.

A more specific object of the invention is the provision of an automatic lock for holding in a 15 signaling position, a visual signal operated by an incoming signal, the lock being operable only when the switchboard is not in manual use.

A further object of the invention is the provision in such a device of mechanism associated 20 with the receiver support which allows an automatic lock for a magnetically operated visual signal to operate when the receiver is in position on its support and which releases said lock when the receiver is removed from its support.

25 Other objects of the invention will in part be obvious and will in part appear hereinafter.

The invention accordingly comprises the features of construction, combination of elements and arrangement of parts, which will be exemplified in the construction hereinafter set forth and the scope of the application which will be indicated in the claims.

For a fuller understanding of the nature and objects of the invention reference should be had 35 to the following detailed description taken in connection with the accompanying drawings, in which:

Fig. 1 is a top plan view with parts broken away of one form of the device of the present 40 invention;

Fig. 2 is a view on line 2—2 of Fig. 1 looking in the direction of the arrows;

Fig. 3 is a sectional view taken on line 3—3 of Fig. 2 looking in the direction of the arrows;

Fig. 4 is a sectional view taken on line 4—4 of Fig. 1 looking in the direction of the arrows;

Fig. 5 is a view of part of the operating mechanism of the present device showing a switch key in locked position;

Fig. 6 is a perspective view of the switch device adapted to be operated by a switch key;

Fig. 7 is a perspective view of portions of the visual signal and the automatic lock associated therewith;

Fig. 8 is a top plan view with parts broken away

of structure similar to that depicted in Fig. 1 having a modified form of receiver support associated therewith; and

Fig. 9 is a sectional elevational view of the structure depicted in Fig. 8 with the automatic visual signal lock omitted.

In telephone switchboards and the like wherein a plurality of incoming circuits are provided it is desirable to have visible signaling means to indicate the particular circuit over which a party 10 is calling. In office units where the party called may frequently be absent when a call arrives it is desirable to have a signaling device which will remain in an indicative condition until the party called has had an opportunity to note the 15 signal. The device of the present invention efficiently performs these and other functions with the provision of an automatic lock for a magnetically operated visual signal and an automatic release operable upon removal of the receiver 20 from its support.

Referring to the drawings like numerals denote like parts throughout. A panel 10 of a telephone switchboard or the like is provided with the usual series of switch keys 11 (only one of 25 which is shown). The panel 10 is mounted between the end supports 12 and 13 respectively which pivotally support a shaft 14. An arm 15 is secured to the shaft 14, the latter preferably being rectangular in cross-section to prevent the 30 arm 15 and other members mounted thereon from rotating with respect thereto. In the first modification depicted in Figs. 1 to 7 inclusive, the arm 15 is disposed adjacent the end support 12 and provided with an extension carrying a receiver hook 16 extending through a slot in the end support 12. A stop member 17 on the end support 12 limits the upward movement of the receiver arm 15 caused by a stressed spring 18 fixed at one end by a pin 19 to the end support 40 12 and secured at the other end to an arm 20 fixed to the receiver arm 15 and preferably made integral therewith. The downward movement of the receiver arm 15 under the weight of the receiver is limited by the stop 21 mounted on the 45 end support 12.

A switch key locking bar 22 is provided with a locking skirt 23 and downwardly extending arms 24 and 25 at the ends thereof, the arms 24 and 25 being pivoted to the end supports 12 and 13 respectively. An arm 26 secured to the locking bar 22 is disposed in the path of a member 27 secured to and preferably made integral with the receiver arm 15.

An arm 28 mounted on the shaft 14 carries a 55

stud adapted to operate the conventional type leaf spring switch 30 supported on the end support 13 which operates to perform well known functions including the connection of the receiver 5 into a circuit when the receiver is removed from its support or the receiver hook 16.

A conventional type of switch key 11 is used in the switchboard associated with the well known leaf spring switch units 31 and 32, each unit being provided with a pair of operating arms 33 and 34 suitably linked together, one having an extending fork 35 adapted to engage a pair of rollers 36-36 mounted on the pivoted switch key lever which is additionally provided with a pair 15 of locking notches 37-37 to cooperate with the locking skirt 23 of the locking bar 22.

The arm 25 of the locking bar 22 is provided with a rigid arm 38 to form therewith a bell crank pivoted to a thrust rod 39 provided with an 20 elongated slot 40 adapted to receive a guide pin 41 mounted upon the end support 13. The end of the thrust rod 39 engages an arm 42 secured to a release bar 43 pivotally mounted between the end supports 12 and 13. A spring 44 anchored at one 25 end to the end support 12 by a pin 45 is fastened at the other end to an arm 46 secured to the release bar 43 to hold the arm 42 in contact with the end of the thrust rod 39.

A magnetically operated visual signal unit 47 30 consists of a magnetic coil 48 having a core 49 and a pivoted armature 50 provided with a switch arm 51. The switch arm 51 is adapted to operate a switch 52 electrically connected to the lower unit of the switch 30 held in a closed position 35 when the receiver arm 15 is held down by the weight of the receiver and for reasons well known to those skilled in the art.

The armature 50 is provided with an ear 53 40 adapted to engage the end 54 of a visual signal arm or bell crank 55 pivoted at 56 to the frame of the magnetic coil 48. The visual signal arm 55 carries adjacent the panel 10 a target 57 adapted to be displayed opposite an aperture 58 in the panel 10 when the magnetic coil 48 is energized.

The signal arm 55 is provided with a downwardly projecting portion 59 to cooperate with an automatic locking member 60 to hold the target 57 in a display position behind the aperture 58. The sides of the member 59 preferably lie upon the circumference of circles described about the pivot axis 56 so that its clearance from a portion of the locking member 60 will be substantially constant to allow the use of a minimum space between the projection 59 and the locking member 60 and a resultant minimum movement of the locking member 60 to lock the visual signal arm 55.

The locking member 60 has the general shape of a gooseneck or hook with the shank 61 thereof 60 extending substantially horizontal and the hook portion 62 thereof lying in a substantially vertical plane. The hook portion 62 is provided with a laterally extending projection 63 adapted to engage the end of the projection 59 on the signal arm 55. The shank portion 61 is provided with a laterally extending finger 64 adapted to be engaged by an arm 65 fixed to the release bar 43 (see Fig. 7). The end of the shank portion 61 is provided with a laterally extending member 65' 70 adapted to be disposed between a pair of stops 66 and 67 mounted upon the frame of the magnetic coil 48 to which is pivoted the locking member 60 at 68. The stops 66 and 67 limit the pivoting movement of the locking member 60.

In Fig. 8 is depicted a modified form of the

switchboard unit which is fitted with a so-called "French phone" unit consisting of a transmitter 69, a receiver 70 and a bar 71 bridged between the transmitter 69 and the receiver 70. The bridging bar 71 is supported by the well known bracket 72 provided with a centrally disposed thrust pin 73 adapted to engage the arm 74 mounted on the rotatable shaft 14. In this modification the thrust pin 73 extends above the bracket 71 when the phone unit is removed therefrom so that when the latter is positioned upon the support 72, the bridging bar 71 will force the thrust pin 73 downwardly to engage and retract the arm 74 to rotate the shaft 14. The arm 15' with the member 27 operates in a manner similar to that of a portion of arm 15 with the member 27 of the first modification. In Fig. 9 is depicted an executive unit with the automatic lock 60 omitted therefrom, the visual target 57 being raised to a display position only during the period of energizing the magnetic coil 48.

In operation a receiver is supported on the hook 16, as shown in the first modification, or a phone unit is supported on the support 72, as in the second modification, when the unit is idle. The weight of the receiver unit depresses the arm 15 of the first described unit or the arm 74 of the second modification, resulting in a partial rotation of the shaft 14 and a stressing of the spring 18. The member 27 engages and depresses the arm 26 on the locking bar 22 thus holding the locking skirt 23 in a position so that the notches 37 in the keys 11 will not be engaged thereby. Such a position of the locking bar 22 depresses the thrust rod 39 partially rotating the release bar 43 against the action of the spring 44 to depress the arm 65 to allow the locking member 60 freedom of movement.

When the magnetic coil 48 is energized by the incoming signal the armature 50 is pulled over 40 adjacent the core 49 with the ear 53 in contact with portion 54 of the bell crank or signal arm 55 which moves upwardly carrying with it the target 57 to a position opposite the hole 58 in the panel 10, until the signal arm projection 59 45 passes beyond the projection 63 of the locking member 60. The shank 61 of the locking member 60 being heavier than the hook-shaped portion 62, gravity causes the shank 61 to fall down until the member 65' engages the stop 66 in 50 which position the locking member projection 63 engages under the end of the signal arm projection 59 to hold the target 57 carried by the signal arm 55 in a display position as depicted in Fig. 4 and, more particularly, in Fig. 7.

The visual signal or target 57 remains in the display position until the receiver unit is removed from its support which allows the stressed spring 18 to move the arm 15 or 15' upwardly thereby freeing the locking bar 22 which due to the excess weight of the overhanging locking skirt 23 and the action of the stressed spring 44 through the release bar 43 and the thrust rod 39 partially rotates the locking bar 22 to a position so that the locking skirt 23 will be allowed to snap into one of the notches 37 of the switch key 11 when the latter is swung up or down to complete the talking circuit signaled. This action is accompanied by a lifting of the thrust rod 39 allowing the release bar 43 to rotate through an angle 70 carrying with it the arm 65 cooperating with the finger 64 on the locking member 60 to move the projection 63 out of the path of the projection 59 on the locking arm 55. This action allows the target 57 to drop out of the display position, the 75

magnetic coil 48 having been energized only during the period of depression of the ringing key by the person sending forth the incoming signal to the switchboard under discussion.

- 5 It will thus be seen that the device of the present invention efficiently attains the objects set forth above particularly since automatic locking means have been provided for a visual signal to maintain the signal in a display position until 10 an attempt has been made to answer an incoming call, the automatic lock being released by the removal of the receiver from its support which function, however, obviously may be performed by a separate manually operated member. The 15 operating mechanism for this automatic lock preferably has been associated with the locking device for the switch keys of the unit and the receiver support so that the usual action followed in attempting to answer an incoming call 20 will result in the operation of the mechanism of the present invention.

Since certain changes may be made in the above construction and different embodiments of the invention could be made without departing from the scope thereof, it is intended that 25 all matter contained in the above description or shown in the accompanying drawings shall be interpreted as illustrative and not in a limiting sense.

30 It is also to be understood that the following claims are intended to cover all of the generic and specific features of the invention herein described, and all statements of the scope of the invention which, as a matter of language, might 35 be said to fall therebetween.

Having described my invention, what I claim as new and desire to secure by Letters Patent, is:

1. In a telephone device, the combination with 40 an incoming circuit having a magnetic coil connected therein when the receiver is in position on the receiver support, and a magnetic coil armature, of a visual signal adapted to be moved to a display position by said armature when said magnetic coil is energized, a biased fastening device 45 vice to maintain said signal in a display position operable only when the receiver is in position on the receiver support, and means to return said fastening device to and hold it in an inoperable position when the receiver is removed 50 from its support.

2. In a telephone device, the combination with a magnetically operated visual signal, a support for the receiver, and a member associated with said support adapted to be retracted by the 55 weight of the receiver when in position on said support, of an automatic lock for said visual signal operable when the receiver maintains said member in a retracted position, and means associated with said member to release said lock and 60 to hold it in an inoperable position when the receiver is removed from said support.

3. In a telephone device, the combination with a receiver support, a spring pressed arm associated with said support to be retracted when

the receiver is in position on said support, a shaft adapted to be partially rotated by the retraction of said arm, a switch-arm locking bar adapted to be held in an inoperable position when said receiver is in position on said support, a magnetic coil in an incoming circuit and an armature, of a visual signal adapted to be moved to a display position by said armature when said magnetic coil is energized, an automatic lock for said visual signal, spring means to hold said lock in an inoperable position, and means associated with said shaft to hold said spring means in a position to allow said automatic lock to operate when the receiver is in position on said support.

4. In a telephone device, the combination comprising a magnetically operated visual signal movable to a display position by a magnetic force, a pivoted locking member operated by gravity to lock said signal in the display position and means associated with a receiver support to be retracted thereby when the latter is retracted by the weight of the receiver, said means including mechanism urged by a spring when the receiver is removed from the support 25 to move said locking member to an inoperable position.

5. In a telephone device, the combination comprising a magnetically operated signal arm having a locking projection, a laterally extending 30 pivoted locking member having a portion on one side of the pivot axis adapted to engage said locking projection to lock said signal arm in a signaling position and a heavier release bar engaging portion on the other side of said pivot axis, a release bar, a spring to normally urge said bar to engage said locking member and move it to a position whereby said locking projection and said locking member are disengaged, a shaft partially rotated by an arm retracted by the receiver 40 when the latter is positioned on the receiver support, and means associated with said shaft to move said release bar to a position whereby said locking member is disengaged from said release bar to allow said locking member to operate automatically.

6. In a telephone device, the combination comprising a pivoted signal arm, a locking projection on said arm, a hooked shaped locking member having an elongated shank portion, a projection on the end of the hooked shaped portion of said locking member to engage the end of said locking member when the relatively heavier shank portion of said locking member is allowed to drop under the action of gravity, a 55 finger mounted on said shank portion, a release bar, an arm on said release bar to engage said finger, a spring to normally urge the engagement between said finger and said arm, and mechanism associated with a receiver arm to hold said release bar in a disengaged position 60 with respect to said finger when the receiver is in position on its support.

HENRY KOCH.
